DESIGN FOR A COMBINED COSMETIC CASE, APPLICATOR, AND MIRROR

Lloyd A. Schmucker, deceased, late of Los Angeles,
Calif., by Marguerite Schmucker, administratrix,
Los Angeles, Calif.

Refiled for abandoned application Serial No.
92,336, May 13, 1940. This application August
5, 1940, Serial No. 94,244

Term of patent 14 years

To all whom it may concern:

Be it known that Lloyd A. Schmucker, late a citizen of the United States, lately residing at Los Angeles, in the county of Los Angeles and State of California, did invent a new, original, and ornamental Design for Combined Cosmetic Case, Applicator, and Mirror, of which the following is a specification, reference being had to the accompanying drawing, forming a part thereof.

This application is a refile for applicant's prior application Serial No. D-72,336, filed May 13, 1940.

Fig. 1 is a perspective view of a combined cosmetic case, applicator and mirror in closed position showing my new design; and

Fig. 2 is a perspective view of the combined cosmetic case, applicator and mirror in open position.

What is claimed is:

The ornamental design for a combined cosmetic case, applicator, and mirror, as shown.

MARGUERITE SCHMUCKER,
Administratrix of the Estate of Lloyd A.
Schmucker, Deceased.
